UNITED STATES PATENT OFFICE.

FREDERICK WILLIAM A. WIESEBROCK, OF NEW YORK, N. Y.

CUT-OFF APPARATUS FOR GAS OR LIQUID SUPPLY PIPES.

SPECIFICATION forming part of Letters Patent No. 760,595, dated May 24, 1904.

Application filed August 27, 1903. Serial No. 170,901. (No model.)

To all whom it may concern:

Be it known that I, FREDERICK WILLIAM A. WIESEBROCK, a citizen of the United States, residing at New York city, Bronx, county and State of New York, have invented certain new and useful Improvements in Cut-off Apparatus for Gas and Liquid Supply Pipes, of which the following is a specification.

This invention relates to an improved cut-off apparatus adapted to be fitted into a pipe-line that carries steam, gas, or liquid under pressure. The apparatus is so constructed that the valve which controls the flow of the steam, &c., is slowly but positively closed in case of breakage or leakage, so that sudden jars are avoided.

In the accompanying drawings, Figure 1 is a vertical longitudinal section of my improved cut-off apparatus; and Fig. 2, a cross-section, partly broken away, on line 2 2, Fig. 1.

The letter *a* represents a housing adapted to be fitted into a length of pipe-line A B, to which it is connected in suitable manner. The pipe-line is adapted to convey steam, gas, or a liquid under pressure from a boiler or reservoir to the place of consumption. Back of its inlet end the housing *a* is flanged, as at *a'*, for the reception of a threaded ring *b*, which constitutes a valve-seat. Against this seat is adapted to bear an outlet-valve *c*, mounted on a valve-stem *c'*, which is guided within a bearing *b'* of seat *b* and a bearing *d'* of a rest *d*. Upon the housing *a* is mounted a cylinder *e*, containing a piston *f*, the rod *f'* of which passes outwardly through a gland *e'* of hood *e*. The rod *f'* carries a collar *f''*, engaged by one arm of a lever *g*, the other arm of which carries a counterbalancing-weight *g'*. The lever *g* is fulcrumed at *g''* to a post *e'*, mounted on hood *e*. This hood is also provided with a vent or blow-off *h*, having cock *h'*. The cylinder *e* is connected to a valve-chest *i*, containing the slide-valve *i'*, movable on spindle *i''*. The valve is operated by hand-lever *j*, fulcrumed at *j'* and engaging valve-tappets *i''*.

The valve-chest obtains its steam, &c., by an inlet-port *k*, that enters housing *a* in front of valve *c*. From the chest *i* one exit-port *k'* leads to the interior of housing *a* back of valve *c*, while a second exit-port *k''* leads from the

chest to the upper section of the cylinder *e* above piston *f*.

The housing is separated from the cylinder by a partition *l*, having a central opening for the passage and guidance of the lower section of piston-rod *f'*. To this lower piston-rod section is pivoted at *m'* the upper end of a link *m*, to the lower end of which are pivoted at *m''* a pair of links *m''' m''*. The link *m'''* is also pivoted at *m''* to the valve-stem *c'*, while the link *m''* is pivoted at *m''* to a support *m'*.

The partition *l* is provided with one or more ports or openings *l'*, which may be closed by upwardly-opening weighted or spring-influenced check-valves *n*.

Within the rear section of housing *a* is fitted an ejector *P*, composed of a nozzle *p* and a surrounding chamber *p'*. The nozzle *p* is arranged in the direction of the flow of the steam through housing *a* and gradually contracts from its inlet to its exit end. Here it opens into the rear contracted end of the chamber *p'*, which merges into a pipe *q*, leading into the pipe-line B. The chamber *p'* communicates, by a channel *r*, with the lower section of cylinder *e* between partition *l* and piston *f*.

The operation is as follows: The apparatus is secured within pipe-line A B, preferably in proximity to the boiler, reservoir, &c., so that the pressure from the latter tends to close the valve *c*. To turn on the supply, the valve *i'* is raised to open port *k'* and close port *k''*, while the cock *h'* is opened. Steam will thus flow into housing *a* to raise the pressure within the housing and pipe-line B. The steam will open valve *n* and enter the lower end of cylinder *e* below piston *f*. When the pressure of the steam against the inner face of valve *c* is equal about to the pressure against the outer face of the valve and the valve is thus balanced, the piston *f* will be raised and will thus open the valve *c* by links *m''' m''*. When the valve has thus been opened, the vent *h'* is closed, and the valve *i'* is lowered to close port *k'* and open port *k''*. In this way steam is admitted above piston *f*, and the pressure on both sides of the piston is equalized. Thus the entire apparatus remains balanced, the tendency of the piston to descend by gravity being counteracted by

weight g' . When the piston has arrived at its maximum elevation, the valve n will close by gravity, and the apparatus is now set to convey the steam, &c., from the boiler through the pipe-line and housing a to the place of consumption.

Under normal conditions the valve c will remain open and the piston f will remain raised, so that a uniform volume of steam is delivered. Under these normal conditions the jet passing through the nozzle p of ejector P will not create any suction in channel r .

If a break or leakage occurs in the rear pipe-section B or the parts connected therewith, the velocity of the steam passing through the apparatus is increased to a considerable extent, so as to create a powerful current in nozzle p . This current will suck the steam from cylinder e below piston f , the steam flowing through channel r , chamber p' , and pipe q into pipe B . The valve n is so weighted that the small difference of pressure thus created between housing a and lower part of cylinder e is not sufficient to lift the valve. As the steam-pressure in the cylinder is thus reduced below the piston, the excess of steam-pressure above the piston causes the latter to gradually descend and to thus gradually close the valve c , such closing being assisted by the impetus of the steam-jet against the outer face of the valve.

It will be seen that by my invention a slow movement of the piston and a corresponding slow movement of the valve either while opening or while closing is obtained. In this way sudden jars to the apparatus or the pipe and its connections are prevented, while a positive and reliable operation of the device is insured.

What I claim is—

1. In a cut-off apparatus, the combination of a housing with a cylinder, an intervening partition, an outlet-valve, a piston in the cylinder connected to said valve, and an ejector communicating with the cylinder, substantially as specified. 40

2. In a cut-off apparatus, the combination of a housing with a cylinder, an intervening partition, an outlet-valve, a piston in the cylinder connected to said valve, a nozzle in the housing, a surrounding chamber, and means for connecting said chamber to the cylinder between piston and partition, substantially as specified. 45

3. In a cut-off apparatus, the combination of a housing with a cylinder, an intervening partition, an outlet-valve, a piston in the cylinder connected to said valve, an ejector communicating with the cylinder below the piston, a port entering the housing, a second port entering the cylinder above the piston, and a valve for controlling said ports, substantially as specified. 50

4. In a cut-off apparatus, the combination of a housing with a cylinder, an intervening partition, an outlet-valve, a piston in the cylinder connected to said valve, an ejector communicating with the cylinder below the piston, a port entering the housing, a second port entering the cylinder above the piston, a valve controlling said ports, and a vent in the upper end of the cylinder, substantially as specified. 55

Signed by me at New York city, (Manhattan,) New York, this 21st day of August, 1903.

FREDERICK WILLIAM A. WIESEBROCK.
